UNITED STATES PATENT OFFICE.

NATHAN W. CONDICT, JR., OF JERSEY CITY, NEW JERSEY.

STAMPING MACHINERY.

SPECIFICATION forming part of Letters Patent No. 275,355, dated April 10, 1883.

Application filed September 22, 1882. (No model.)

To all whom it may concern:

Be it known that I, NATHAN W. CONDICT, Jr., a citizen of the United States, and a resident of Jersey City, New Jersey, have invented 5 certain Improvements in Stamping Machinery, of which the following is a specification.

My invention relates to improvements, fully described hereinafter, in that class of stamping mechanism in which minerals and other 10 materials are pulverized by power-operated stamp-rods combined with mortars.

In the accompanying drawings, Figure 1, Sheet 1, is a general view of apparatus with which my invention is connected; Fig. 2, a 15 vertical section of the mortar and appliances connected therewith; Fig. 3, Sheet 2, a plan view, partly in section, of Fig. 2; and Fig. 4, a sectional plan on the line 1 2, Fig. 2.

Referring to Fig. 1, A is a substantial frame, 20 carrying at the top two cylinders, B, one only being shown in the drawings. The pistons of these two cylinders are connected to stamp-rods C, the lower ends of which operate on minerals or other material to be pulverized in 25 the mortars L, which are supported on a foundation separate from that of the frame. Sometimes I use a single steam-cylinder with one mortar and one stamp-rod.

A description of the steam-stamp will not be 30 necessary, as my invention relates to the stamp and mortar L and its connections, and is not restricted to any specific mechanism for operating the stamp. On the top of this mortar is a chamber, L', to which air is admitted freely, 35 as explained hereinafter. This chamber communicates through a pipe, M, with a receiver, M', and the latter through a pipe, N, with the exhaust-opening of a fan-blower, N', the discharge-opening of the latter communicating 40 through a pipe, P, with a second receiver, P'. The air rushing through the chamber of the mortar carries with it the finely-pulverized material through the pipe M, the heavier and coarser particles falling to the bottom of the 45 receiver M' and the finer particles passing through the pipe N, blower N', and pipe P into the receiver P'.

It should be understood that I do not claim 50 in this application this exhausting mechanism, which, together with the steam stamp and frame, have been briefly described, so as to

better explain the invention illustrated in Figs. 2, 3, and 4.

The mortar L is a substantial casting containing the anvil Q, which is let into the bottom of the mortar, and is confined thereto by the annular tapering lining Q' and a substantial ring, R, secured to the flanged top of the mortar.

I prefer to use a packing-ring, 9, of suitable 60 yielding material, between the ring R and flanged top of the mortar, and a similar packing-ring, 10, between the upper edge of the lining and the ring, the metal in both cases being recessed to receive the packing. 65

Both the anvil and sides of the mortar soon become worn by the violent action of the stamp; hence the advisability of a detachable lining and anvil, the former of which can be readily removed after the withdrawal of the ring R. 70 The anvil, however, is liable to become jammed in its place; but it can be easily dislodged by a wedge-like tool driven through an orifice, v, which I make in the mortar for this purpose.

The chamber L' above referred to is formed 75 by a perforated casing, S, secured to the ring R, and provided with a cover, S', having a central opening, w, through which passes the lower end of the stamp-rod C. This opening w is closed partly by the stamp-rod, partly by a 80 ring, w', on the same, and partly by a flexible ring, y, of canvas or other available material, the inner edge of the ring y being attached to a flange on the ring w' and the outer edge to the cover S' of the casing, or to any available 85 part of the same. The inner edge of the flexible ring might be secured directly to a flange on the stamp-rod; but, preferring that the latter should be at liberty to turn, I make the ring w' in two parts, so that it can be readily ad- 90 justed to its place between two collars on the stamp-rod and then bolted together, after which the canvas ring may be applied. It should be understood that the ring w' is fitted loosely to the stamp-rod, so that the latter can turn freely 95 in the ring.

Within the chamber L', and at a short distance from the perforated casing S, there is an annular deflector, 3, which compels the air passing through the perforations of the said 100 casing to take the course pointed out by the arrows.

The mineral or other material to be crushed is introduced into the chamber L' through the inlet-pipe 4, to the lower end of which is pivoted a valve, 5, the latter being connected by 5 a link, 6, to the short arm of the weighted lever 7, pivoted to a stand on the cover S'. To the top of this cover S' is secured the annular box 8, the continuity of which, as shown in Fig. 3, is interrupted to afford room for the 10 inlet-pipe 4 and the lever for operating the valve of the same. That portion of the cover S' which is within the limit of the box 8 is perforated, and the air which, through the agency of the fan-blower, rushes into the chamber L' 15 will pass through these perforations into the box 8, and thence into the pipe M, described above, the air carrying with it the particles of pulverized mineral.

The canvas ring y is of sufficient extent to 20 permit the rising and falling of the stamp to the required distance.

In some cases the pulverizing may take place without the introduction of air into or its discharge from the mortar, the material being 25 simply confined in the said mortar until reduced to the desired condition, provision being made for the removal of the pulverized mass; but in most cases the plan above described of withdrawing the powder will be adopted.

30 I claim as my invention—

1. The combination of the mortar, perforated casing, stamp-rod, and flexible ring y with the shield or deflector 3, substantially as specified.

2. The combination of the mortar, the casing, the stamp-rod and its two collars, the two-part ring w', and the flexible ring y, substantially as described. 35

3. The combination of the mortar, the casing, stamp-rod, and flexible ring with the box 8, communicating with the interior of the casing, and having an outlet, M, all substantially as set forth. 40

4. The combination of the mortar, the casing, the deflector, and box 8, communicating with the interior of the casing, and having an outlet, M, all substantially as specified. 45

5. The combination of the mortar L, anvil Q, lining Q', and ring R, substantially as specified.

6. The combination of the mortar, anvil, lining, and ring R with packing-rings 9 and 10, as set forth. 50

In testimony whereof I have signed my name to this specification in the presence of two subscribing witnesses.

NATHAN W. CONDICT, JR.
